UNITED STATES PATENT OFFICE.

LOUIS NARCISSE PRUDHOMME, OF BERMUDA, LOUISIANA.

SADDLE-BAG.

SPECIFICATION forming part of Letters Patent No. 761,782, dated June 7, 1904.

Application filed August 8, 1901. Renewed May 6, 1904. Serial No. 206,693. (No model.)

To all whom it may concern:

Be it known that I, LOUIS NARCISSE PRUDHOMME, a citizen of the United States, residing at Bermuda, in the parish of Natchitoches 5 and State of Louisiana, have invented certain new and useful Improvements in Saddle-Bags, of which the following is a specification.

My invention relates to saddle-bags; and its primary object is to provide a device of 10 this character which will thoroughly protect its contents from the weather and be convenient and durable in use.

The improvement is designed especially for use in the transportation of the mails where 15 horseback service is necessary, as in rural free delivery, &c. With this end in view I provide a device provided with a series of pockets or receptacles of ready access for the reception of mail-matter and designed to be applied directly to a horse without the use of a saddle and fastened to the horse by means of girths and a breast-strap and crupper attached to the same.

The invention consists in the novel construction, arrangement, and combination of 20 parts hereinafter described, illustrated in the accompanying drawings, and pointed out in the appended claims.

Referring now to the drawings forming a 25 part of this specification, Figure 1 is a top plan view of the bag spread out and the top cover broken partly away in order to show the manner in which the flap-cover is fastened to the sides of the bag. Fig. 2 is a side view 30 of the bag with one side of the top cover and flap-cover broken away. Fig. 3 is a horizontal sectional view of the bag, taken on line *a b* of Fig. 1.

Similar characters of reference indicate like 35 parts throughout all the figures of the drawings.

In the drawings, 1 designates the skirt or main body portion of the bag, of leather, canvas, or other suitable and convenient material and provided with girths 2 and a breast-strap 3 and crupper 4. To each side of this 45 skirt there is secured a strip of material 5, forming a receptacle or pocket, divided into

compartments or bags *c*, *d*, and *e*, the bottoms and sides thereof of which are made up of 50 flexible leather foldings *f*, so as to adapt them to varying capacities.

6 designates the flap-cover, which is designed to close the mouths of the bags and fit down flat with the sides thereof. This cover is provided with a series of openings 7, which are designed to take over a series of staples or loop-eyes 8, secured to the sides of the bags or receptacles.

9 designates a piece of metal or stiff leather 60 for protecting the openings 7.

10 designates a strap sewed at one end to the flap-cover 6 and designed to securely fasten the same to the sides of the bags and close the mouths thereof by passing its free end through 65 the staples 8 and then fastening its free end by means of a padlock 11 or other suitable fastening.

12 designates a cover of oil-cloth, rubber, or some other suitable and convenient material and designed to fit down and be fastened to the sides of the bags by means of straps and buckles 13.

14 designates straps and buckles secured to the flap-cover 6 and designed to hold rolls of 75 blankets, guns, &c.

It will be observed that the cover 12 is made wider and longer than the skirt 1, so that the same will cover the bags when they are filled to their full capacity.

Having thus described my invention, what I claim, and desire to secure by Letters Patent, is—

1. A saddle-bag, comprising a suitable skirt, forming the main body portion thereof, two 85 strips of material secured to the sides thereof by means of flexible pieces of material, forming pockets, divided into suitable compartments or bags, flap-covers secured to the skirt above the mouths of said compartments 90 or bags and closing the same, means for securing said flap-covers to the sides of said bags, and a cover secured at its center to the skirt intermediate the said bags and covering the same, substantially as described. 95

2. In a saddle-bag, the combination with a

skirt forming the main body portion thereof; of strips of material secured to the sides thereof by means of flexible pieces of material forming compartments or bags, flap-covers secured to said skirt above the mouths of said bags and closing the same, means for securing said flap-covers to the sides of said bags, and a cover secured at its center to the skirt and covering

the same, substantially as and for the purpose set forth.

In testimony whereof I have affixed my signature in presence of two witnesses.

LOUIS NARCISSE PRUDHOMME.
